UNITED STATES PATENT OFFICE.

SOREN A. EGEKVIST, OF MINNEAPOLIS, MINNESOTA.

COUNTERWEIGHTED DOOR.

1,202,039.

Specification of Letters Patent. Patented Oct. 24, 1916.

Application filed June 23, 1916. Serial No. 105,320.

To all whom it may concern:

Be it known that I, SOREN A. EGEKVIST, a citizen of the United States, residing at Minneapolis, in the county of Hennepin and State of Minnesota, have invented certain new and useful Improvements in Counterweighted Doors; and I do hereby declare the following to be a full, clear, and exact description of the invention, such as will enable others skilled in the art to which it appertains to make and use the same.

My invention relates to improvements in counterweighted doors; and, to this end, it consists of the novel devices and combinations of devices hereinafter described and defined in the claims.

In the accompanying drawings, which illustrate the invention, like characters indicate like parts throughout the several views.

Referring to the drawings, Figure 1 is a front elevation of a baker's proof-box; having the invention incorporated therein; Fig. 2 is a transverse vertical section taken on the line 2—2— of Fig. 1 with some parts shown in different positions by means of broken lines; Fig. 3 is a detail view, principally in vertical section taken on the line 3—3— of Fig. 1, on an enlarged scale; and Fig. 4 is a detail view, principally in horizontal section taken on the line 4—4— of Fig. 1, on an enlarged scale.

In the drawings, the invention is shown incorporated in a baker's proof-box, but it is, of course, understood that the same may be used in connection with any other door opening, wherein such a door would be of use. Proof-boxes, as is well known, are for holding bread, rolls, etc., during the raising thereof, and are heated by introducing steam therein.

The proof-box 1 is a rectangular sheet metal structure, having its entire front open to afford a door opening therefor. This proof-box 1 is supported in a skeleton frame 2, having a rectangular casing 3 and a door sill 4 for the door opening thereof. Within the proof-box 1, is a multiplicity of imperforate shelves 5 on which the bread and rolls are placed. For the purpose of this case, it will not be necessary to illustrate the means for heating the proof-box 1.

The improved counterweighted door comprises upper and lower sections 6 and 7, respectively, connected by hinges 8 at their adjacent horizontal edges for outward

swinging movement. When the door is closed, the sections thereof are alined and in flat engagement with the outer face of the casing 3 and overlap the same to afford a tight joint therebetween. It is important to note that the lower door section 7 is slightly longer than the upper door section 6.

Angle irons 9 are secured to the uprights of the casing 3 to afford therebetween channel guides 10. Metal faced filling strips 11 are placed between the angle irons 9 and casing 3 to reduce the depth of the channels 10 and also assist in rigidly securing said angle irons to the casing. A horizontal hinge rod 12 has its ends mounted in the filler strips 11 and rearwardly projecting flanges of the angle irons 9. The door sections 6 and 7 are suspended from this hinge rod 12 over the door sill 4 for vertical swinging movement by a yoke-like hinge plate 13, which straddles said hinge rod, embraces the upper horizontal edge portion of the upper door section 6 and is rigidly secured thereto.

Secured to the lower corners of the lower door section 7, is a pair of roller-equipped trunnions 14, which extend into the vertical guides 10 and connect said door section thereto for pivotal and vertical sliding movements. From the above description, it is evident that the hinge connections 8, 12—13 and the trunnions 14 connect the improved door to the casing 3, for toggle-like opening and closing movements.

Three arms 15 are secured to the outer face of the upper door section 6 and their upper end portions are offset outward therefrom and extended above the proof-box 1. A counterweight 16 in the form of a horizontal bar, is rigidly secured to the upper extremities of the arms 15. This counterweight 16, being located outward of the vertical plane through the hinge rod 12, tends to hold the door sections 6 and 7 alined and in flat engagement with the casing 3. A pair of hand holds 17 are secured to the upper outer horizontal edge portion of the lower door section 7.

To open the improved door, the operator pulls outward on the hand hold 17, which buckles the door sections 6 and 7 and causes the trunnions 14 to travel upward in the guide channels 10. When the door sections have been buckled sufficiently to carry the counterweight 16 rearward of said vertical plane, said door sections will be held by the counterweight whenever set, depending

whether it is desirable to completely open the door or only partly open the same.

When the improved door is moved to its extreme open position, as shown by broken lines in Fig. 2, the sections thereof are in substantially parallel relation, with respect to each other, and slightly out of a true horizontal position. The slightly increased length of the lower door section 7 over the upper section 6 permits said sections to assume this relation, when in extreme open position. A stop rail 18 on the top of the frame 2 is engaged by the arms 15, when the door is completely open, to prevent the counterweight 16 from coming into contact with the top of the box 1 or frame 2.

The above described door has been put in successful use and has proven highly efficient for the purpose had in view.

20 What I claim is:—

1. The combination with a door opening and a casing therefor, of a door for the door opening comprising upper and lower sections, hinges connecting the upper door section to the casing and the one door section to the other for vertical opening and closing movements, means connecting the lower door section to the casing with free-

dom for vertical sliding and pivotal movements, and a counterweight on the upper 30 door section and movable from one side to the other of the vertical plane through the hinge connecting the upper door section to the casing.

2. The combination with a door opening 35 and a casing therefor, of a door for the door opening comprising upper and lower sections, said lower door section being slightly longer than the upper door section, a horizontal hinge connecting the upper door section to the casing, a hinge connecting the two door sections, means connecting the lower door section to the casing for pivotal and vertical sliding movements, an arm carried by the upper door section, and a counterweight on the upper door section and movable from one side to the other of the vertical plane through the hinge connecting the upper door section to the casing. 40

In testimony whereof I affix my signature 50 in presence of two witnesses.

SOREN A. EGEKVIST.
